(57) **CLAIM**

The ornamental design for an intelligence robot, as shown and described.

DESCRIPTION

FIG. 1 is a front elevation view of an intelligence robot; FIG. 2 is a rear elevation view of an intelligence robot; FIG. 3 is a left side elevation view of an intelligence robot; FIG. 4 is a right side elevation view of an intelligence robot; FIG. 5 is a top plan view of an intelligence robot; FIG. 6 is a bottom plan view of an intelligence robot; FIG. 7 is a first perspective view of an intelligence robot; and, FIG. 8 is a second perspective view of an intelligence robot. Portions of the figures shown in broken lines depict portions of the intelligence robot and form no part of the claimed design.
